INVENTOR.
Charles C. Hansen
BY
Robert H. Ogden
HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

VALVE FOR ROCK DRILLS.

Application filed November 18, 1926. Serial No. 149,137.

This invention relates to rock drills, but more particularly to a distributing valve for fluid actuated rock drills of the hammer type.

5 The objects of the invention are to obtain a quick and positive valve action and to insure a heavy blow of the hammer piston against the working implement.

Other objects will appear hereinafter.

10 In the drawings forming part of this specification,

Figure 1 is a sectional elevation of a rock drill showing the valve in position to admit pressure fluid to the rearward end of the 15 cylinder,

Figure 2 is a similar view showing the valve in position to admit pressure fluid to the front end of the cylinder, and

Figure 3 is a view similar to Figures 1 and 20 2 showing a modification of the invention.

Referring to the drawings and at first more particularly to Figures 1 and 2, A represents a cylinder having a free exhaust port B. A reciprocatory hammer piston C is disposed in the cylinder A and in this instance has a plain reduced forward extension D to deliver blows of impact to a working implement (not shown). The extension D cooperates slidably with a head E which forms a 25 closure for the front end of the cylinder, the rearward end of the cylinder A being sealed by a head F.

Disposed on the cylinder A is a valve chest G having a bore designated generally by H. 30 The outer portions J of the bore H may be of uniform diameter and in the present instance are sealed by hollow plugs K and L through which extends a bolt O whereby the said plugs K and L are clamped securely in assembled position.

Intermediate the inner ends of the plugs K and L is a valve chamber P having a reduced bore Q at its rearward end. The rearward end of the bore Q is in this instance 45 in constant communication with the atmosphere through an exhaust passage R.

Pressure fluid for operating the drill may be introduced into the valve chamber P through a suitable connection S communicating with a central port T in the valve cham-

ber through a passage U. An inlet passage V is formed in the cylinder A to communicate at one end with the valve chamber P forwardly of the central port T and at its other end with the front end of the cylinder A. A similar inlet passage W in the rearward end of the cylinder A affords communication between the forward end of the cylinder and the valve chamber P rearwardly of the central port T. In the present instance, a small passage X is formed in the valve chest G to establish communication between the central port U and the rearward inlet passage W.

The distribution of the pressure fluid entering the central port T is effected by a distributing valve Y preferably of the sleeve type. The valve Y in this instance has an enlarged bore Z to cooperate slidably with an enlarged portion b of the bolt O and also has a smaller bore c to cooperate slidably with a reduced portion d of the bolt O. In this way is formed a pressure chamber e in the valve Y. An end wall e' in the chamber e serves as an actuating and holding face against which pressure fluid may act to assist in throwing the valve rearwardly and to hold it in said rearward position. The pressure chamber e is in constant communication with the central port T through radial passages f formed in a central head g of the valve which in this instance has an outer actuating face g' and controls the central port T.

An end head h of the same diameter as the central head g is formed on the front end of the valve and in this instance has a forward actuating face j intermittently exposed to pressure fluid admitted from the cylinder A through a kicker passage k to a pressure chamber o in the front end of the valve chamber P for throwing the valve Y rearwardly. An exhaust port p is formed in the valve chest G near the forward end of the chamber P to permit the escape of pressure fluid admitted into the expansion chamber o and also to permit the exhaust of air compressed by the piston C in the front end of the cylinder. This exhaust port p is controlled by the end head h.

In the operation of the device with the valve Y and the piston C in the positions illustrated in Figure 1, pressure fluid entering the port T will pass over the rearward actuating face g' of the central head g and thence will flow through the inlet passage W into the rearward end of the cylinder to impel the piston forwardly. Immediately prior to the uncovering of the free exhaust port B by the piston C, the kicker passage k will be uncovered and a portion of the pressure fluid in the rearward end of the cylinder will flow through the said kicker port k into the expansion chamber o and, assisted by the pressure fluid in the pressure chamber e, will throw the valve to its rearwardmost limiting position. However, the valve Y is not thrown rearwardly until the piston C is about to deliver its blow against the working implement so that the air compressed by the piston C in the front end of the cylinder may be freely expelled through the front inlet passage V and through the valve chamber P between the heads g and h and through the exhaust port p. The valve, however, will be thrown rearwardly before all the air compressed by the piston will be exhausted to the atmosphere, thus entrapping a small portion of compressed air in the front end of the cylinder to slightly cushion the blow of the hammer piston C.

About the time that the valve Y reaches its rearwardmost limiting position the expansion chamber o will be placed in communication with the exhaust passage p thus permitting the escape of the pressure fluid utilized for actuating the valve rearwardly to the atmosphere. It will be observed that the pressure fluid is not exhausted from the expansion chamber o until the valve has practically traveled the entire distance rearwardly. In this way is obtained a positive and quick valve action and the tendency of the valve to flutter will be entirely eliminated.

While the valve is in its rearward position the pressure fluid existing in the pressure chamber e acting against the actuating face e' will hold the valve rearwardly thus permitting a free flow of pressure fluid from the central port T through the valve chamber P and through the front inlet passage V into the front end of the cylinder to impel the piston C rearwardly. After the piston C overruns the exhaust port B the air in the rearward end of the cylinder A will be compressed by the piston and, being augmented by pressure fluid flowing through the small port X, will act against the actuating face g' of the central head g and will again throw the valve forwardly to admit pressure fluid to the rearward end of the cylinder, thus completing the cycle of operations.

In the modified construction shown in Figure 3 a valve q is disposed in the valve chamber P and has a reduced forward extension r slideable in an expansion chamber s in the forward sealing plug K'. A passage t leading from the central port T to the front end of the expansion chamber s conveys pressure fluid thereto to act against a holding face u on the end of the reduced extension r for holding the valve rearwardly after it has been thrown by the pressure fluid entering the expansion chamber s through the kicker passage k. The operation of this modified form of valve is similar in all respects to that of the preferred modification with the exception that in this instance the end face of the reduced portion r constitutes the holding face which is constantly exposed to pressure fluid to assist in throwing the valve rearwardly and for holding the valve in its rearwardmost position.

I claim:

1. In a fluid actuated rock drill, the combination of a cylinder having a free exhaust port, a hammer piston in the cylinder, a valve chest having a chamber with a reduced bore at one end, inlet passages leading from the chamber to the cylinder, a distributing valve in the chamber having a central head and an end head of the same diameter, an actuating face on one end of the valve intermittently exposed to live pressure fluid for throwing the valve in one direction, the opposite end of the valve being constantly exposed to atmospheric pressure, a holding face of smaller area than the actuating face constantly exposed to live pressure fluid for holding the valve in thrown position, an opposed actuating and holding face on the central head intermittently exposed to air compressed by the piston for throwing the valve and intermittently exposed to live pressure fluid flowing to one end of the cylinder for holding the valve.

2. In a fluid actuated rock drill, the combination of a cylinder having a free exhaust port, a hammer piston in the cylinder controlling the exhaust port, a valve chest having a valve chamber with a reduced bore at one end, inlet passages leading from the valve chamber to the cylinder, a distributing valve in the chamber having a central head and an end head of the same diameter, one end of the valve being constantly exposed to atmospheric pressure, a pressure chamber in the end of the valve chamber, a kicker passage intermittently conveying pressure fluid from the cylinder to the pressure chamber to act against the other end of the valve for throwing the valve to one position, a pressure chamber in the valve having an actuating face constantly exposed to live pressure fluid for holding the valve in such thrown position, an actuating and holding

face on the central head intermittently exposed to air compressed by the piston for throwing the valve to another position and intermittently exposed to live pressure fluid flowing to the rearward end of the cylinder for holding the valve in thrown position, and an exhaust port controlled by the end

head for exhausting live pressure fluid from the end of the valve chamber and for exhausting air compressed by the piston in the front end of the cylinder.

In testimony whereof I have signed this specification.

CHARLES C. HANSEN.
